BEVERAGE CONTAINER

Thomas M. Davidson, Coalwood, W. Va.

Application January 24, 1939, Serial No. 252,649

3 Claims. (Cl. 229—7)

My invention relates generally to temporary containers for beverages, and particularly to a paper or other material beverage cup having a removable lid, in which cup is incorporated a drinking straw, and an important object of my invention is to provide a simple and efficient and inexpensive arrangement of this character.

Another important object of my invention is to provide in a beverage cup of the character indicated above, means in connection with the drinking straw to seal the container against the escape of liquid before the lid or cover is removed.

Other important objects and advantages of my invention will be apparent from a reading of the following description taken in connection with the drawing, wherein for purposes of illustration I have shown a preferred embodiment of my invention.

In the drawing:

Figure 1 is a general transverse vertical sectional view taken through the embodiment and showing the drinking straw in the collapsed inoperative position in full lines, and showing the drinking straw in extended operative position in dotted lines.

Figure 2 is a side elevational view of the drinking straw assembly.

Figure 3 is a horizontal sectional view taken through Figure 1.

Referring in detail to the drawing, the numeral 5 generally designates the cup or container which although primarily designed for manufacture in paper material, is suitable to be manufactured in any other adaptable material, as is the drinking straw to be described. The walls 6 of the cup taper downwardly so that the upper extremity indicated by the numeral 7 has a larger diameter than the bottom 8. Proceeding from the point 7 is the dome-like portion 9 which tapers inwardly and upwardly and has a right angular flange 10 on its upper end forming a seat for the beveled edged lid or cover 11. An upstanding flange 12 projects upwardly from the part 10. The cover or lid 11 is to be held in place in the usual frictional or any other suitable manner.

The drinking straw assembly is generally designated 13 and this comprises an outer tube 14 which has one side glued or otherwise suitably fastened to one side of the wall 6 with the lower open end 15 adjacent the bottom 8 and with the upper end designated by the numeral 16 located on a level below the point 7. An inwardly tapered portion 17 is connected to the lower end of a reduced diameter portion 18 on the upper

end of the tube 14, the portion 17 defining a shoulder to be engaged by the angulated shoulder 19 on the enlarged portion 20 of the "straw" 21, the portion 20 being of an exterior diameter to slide snugly in the outer tube 14, and the main part of the tube 21 being of a diameter to slide snugly in the reduced portion 18 of the tube 14. The frustro-conical part 9 on the container 5 has at one side an opening of a suitable size to pass the tubular mounting 22 which depends from an acutely angulated disk 23. The tube 22 receives the upper part 18 of the tube 14 and is secured thereto by means of glueing or like attaching means, with the underside of the disk 23 similarly secured to the top of the wall portion 9.

The main part of the "straw" 21 is of a sufficient length to extend above the top of the container to a height suitable for use in the ordinary manner of a straw. On the upper end of the straw is a cap 24 which has secured to one side an inwardly pressing spring-finger 25 which while engaged with the upper end of the "straw" holds the cap securely in place and prevents escape of liquid through the straw from the interior of the container, the cap being readily removable and replaceable for use on the "straw."

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

Having described the invention, what is claimed as new is:

1. A beverage container comprising a receptacle, a drinking straw assembly mounted through a wall of the receptacle, said assembly comprising a mounting including a stationary tube secured within the receptacle, a tubular element telescoped on and fixed to said stationary tube and to the wall of the receptacle, and a "straw" snugly slidable in said stationary tube.

2. A beverage container comprising a receptacle, a drinking straw assembly mounted through a wall of the receptacle, said assembly comprising a mounting including a stationary tube secured within the receptacle, a tubular element telescoped on and fixed to said stationary tube and to the wall of the receptacle, and a "straw" snugly slidable in said stationary tube, said stationary tube and said "straw" having interengageable shoulders to provide a liquid seal.

between them while the "straw" is in the extended operative position.

3. A beverage container comprising a receptacle, a tubular member located within the receptacle with its upper end mounted to a wall of the receptacle and a straw forming member

slidable in said tubular member and said straw forming member and said tubular member having inter-engageable shoulders to provide a liquid seal between them when the straw is in extended operative position.

5

THOMAS M. DAVIDSON.
